UNITED STATES PATENT OFFICE.

LEWIS E. WATERMAN, OF ROCKFORD, ILLINOIS, ASSIGNOR TO EMERSON-BRANTINGHAM COMPANY, OF ROCKFORD, ILLINOIS, A CORPORATION OF ILLINOIS.

TWO-WAY PLOW.

1,262,722.

Specification of Letters Patent. Patented Apr. 16, 1918.

Application filed July 10, 1916. Serial No. 108,457.

To all whom it may concern:

Be it known that I, LEWIS E. WATERMAN, a citizen of the United States, residing at Rockford, in the county of Winnebago and State of Illinois, have invented certain new and useful Improvements in Two-Way Plows, of which the following is a specification.

This invention relates in general to plows, and particularly to reversible or two-way plows adapted for hillside plowing. More specifically, the invention relates to the class of two-way plows having bails on which the plow beams and carrying wheels are mounted and which are operated either manually by hand levers or by power from the carrying wheels to raise the plows. By reason of the fact that the carrying wheels are customarily mounted on fixed axes on the bails the wheels are maintained in fixed vertical relation with respect to the frame whether in raised or lowered position. The result of such a construction is that the carrying wheel traveling in the furrow can not effectively resist the side thrust of the plow, consequently, uneven strains on the bearing of the furrow wheel and an increase in the draft result. Furthermore, the wheel treads in the furrow in so nearly an upright position as to strike against and tear down the side wall thereof, thus clogging the wheel, increasing the draft and causing the wheel to frequently run out of the furrow, all of these undesirable features being accentuated in proportion to inclination of the hill-side being plowed.

My invention aims, primarily, to overcome these objectionable features and to this end I have devised a two-way plow in which the carrying wheels may be tilted laterally relatively and with respect to the frame so as to most efficiently serve their purpose as carrying members and to effectively resist the side thrust of the plows, thus materially decreasing the draft.

More particularly, I have provided a two-way plow in which each carrying wheel and its adjacent plow may be raised and lowered in unison and the carrying wheels will be automatically canted laterally during such movement so that when the plow is raised the wheel will tread in a vertical position relatively to the frame and when the plow is lowered the wheel will tread in an inclined position in its furrow, canted out-

wardly with respect to the vertical axis of the frame.

Other objects and attendant advantages will be apparent as the invention becomes better understood by reference to the following description when considered in connection with the accompanying drawings, in which—

Figure 1 is a side elevation of a two-way plow embodying my improvements, showing the left hand moldboard in working position;

Fig. 2 is a side elevation of the plow showing the right hand moldboard in raised position;

Fig. 3 is a plan view of the plow; and

Fig. 4 is a rear view thereof.

The frame of my improved plow is of comparatively simple design consisting of a cross beam 6 having rearwardly turned ends 7, an angle iron beam 8 positioned above the beam 6 and segment brackets designated generally by reference character 9 to which the ends of the cross beams are bolted. A pair of plow carrying bails 11 are pivotally mounted at their inner ends on a common pivot bolt 12 carried by rearwardly projecting supporting plates 13 bolted to the cross beam 6 and are pivotally mounted at their outer ends on pivot bolts 14 concentric with the bolts 12. It will be noted that each bail is formed in two parts, the outer arm 15 being a separate part. This arm at its free end is provided with a sleeve 16 through which the forwardly turned outer end 17 of the main part of the bail projects longitudinally of the machine. A set screw 18 secures the arm 17 fixedly to the sleeve 16 so that the bail is in effect an integral structure. Each bail carries a suitable plow beam 19 equipped with a moldboard. A driver's seat may be mounted on the frame. A tongue 21 is suitably connected to the frame, and as is well understood in the art means, not shown in the present instance, may be provided for adjusting or swinging the tongue laterally with respect to the frame to take care of the side draft of the implement when plowing on different grades.

Upon the arm 17 of each bail is pivotally mounted a yoked bracket 22 carrying an axle 23 secured rigidly thereto, and on each axle is journaled and suitably secured a carrying wheel 24 equipped at its inner end

with a toothed ratchet wheel 25. By reason of this construction, each carrying wheel and its plow beam may be raised and lowered with respect to the frame by simply 5 swinging the bail on its pivots and the wheels may be tilted relatively to the frame about the bail portions or arms 17.

A single mechanism comprising a hand lever and a coöperating segment 9 serves 10 to operate each bail and to control the tilting movement of each carrying wheel relatively to its bail and the main frame. In effecting these movements the hand lever is swung backwardly and forwardly by hand 15 in the usual manner to rock the bail and at the same time a lateral tilting movement is imparted to the lever by the coöperating segment which is mounted at an angle to the longitudinal axis of the machine.

20 The segment 9 having a toothed underface 26 is shaped to extend outwardly and rearwardly from the cross-beam, thus providing a laterally inclined cam way 27. The hand lever 28 fixed to a bracket 29 in turn rigidly 25 secured or formed integrally with the yoked part 22 is equipped intermediate its ends with an inwardly extending bracket 31 that carries a pair of cone shaped rollers 32 arranged to engage the inner and outer sides 30 of the segment 9 so as to slidably associate the hand lever with the segment and maintain the lever in fixed relation thereto at all times. Thus when the lever 28 is swung back and forth on the pivot axis of the 35 bail to raise and lower its plow, it is also tilted laterally due to the lateral inclination of the segment, this lateral tilting movement of the lever being independent of the bail on the axis of the arm 17 thereof. Since 40 the lever 28 is in effect integral with the axle 23, the latter will also be moved about the axis of the arm 17. The effect of this construction is to cant or tilt the carrying wheel from a vertical to an outwardly inclined position such as is shown at the left 45 of Fig. 4 when the hand lever is moved from its foremost to its rearmost position to lower the plow into the ground.

Means are provided for locking the hand 50 lever to the segment and for operating the lever by power to raise its plow to inoperative position. This means comprises a dog carrier 33 embracing and slidably mounted on the lever 28 and equipped on its inner 55 side with an integral dog 34 adapted to engage the notched face 26 of the segment.

An expansion spring 35 operating between the parts 33 and 29 constantly urges the dog 34 toward the notched face 26. A dog 36 60 slidable in a guideway 37 integral with the bracket 29 and connected at 38 to the carrier 33 is adapted to be moved into and out of engagement with the ratchet wheel 25 by movement of said carrier 33 longitudinally 65 on the lever. The dogs 34 and 36 are so

relatively arranged that when the dog 34 is engaged in the face 26, the dog 36 will be disengaged from the ratchet wheel and so that the dog 34 may be moved out of engagement before the dog 36 is moved into 70 engagement with its respective toothed face. The dog carrier 33 normally urged into locking connection with the segment 9 by means of the spring 35 may be operated by a hand lever 39 to withdraw the dog 34 75 from its segment. For this purpose the hand lever 39 mounted on the lever 28 and connected to the slide member 33 through means of a link 41 may be moved in a counterclockwise direction viewing Fig. 1. 80 A second lever 42 mounted on the lever 28 is provided for moving the dog carrier 33 farther downwardly to engage the dog 36 with the ratchet wheel. The lever 42 is connected to the slide member 33 through means of a link 43 and it will be noted that this further downward movement by the lever 42 does not affect the lever 39 because of the slot connection between the latter and the link 41. The lever 42 may also be operated by means of a foot lever 44 pivoted at 45 to a depending extension of the segment 9 and having its outer end connected at 46 to a link 47 which is connected at 48 to the lever 42. By means of the foregoing 90 operating mechanism the operator may cause the plow to be raised from the ground by power either by pressing forwardly on the foot lever 44 or by operating the hand lever 42, which operation as already explained 100 will disconnect the lever 28 from the segment and engage the dog 36 with the ratchet wheel, causing the plow to be lifted by the rotation of said wheel. When the plow is elevated to a predetermined position, the dog 36 will be automatically disengaged from the ratchet wheel and simultaneously the dog 34 will be moved into engagement 105 with the notched face of the segment thereby locking the plow in raised position. This result is effected by means of a roller 49 mounted on the upper end of the dog carrier 33, which roller engages and is operated by an inclined cam 51 disposed forwardly on the peripheral face of the segment 9, it being obvious that as the lever is swung to its foremost position the roller 49 will be moved up the incline 51 and operate the dog carrier 33 for the purpose described. 110

120 It will be understood that the plow and wheel carrying and operating mechanism at each side of the frame is identical in construction and operation and that when plowing on a side hill the plows are used 125 alternately in plowing back and forth. For instance, with the left hand plow in operation the plow is raised at the end of the furrow, the implement turned about and the right hand plow lowered into the ground to 130

turn up the next new land. In plowing in this manner with my improved plow, it will be apparent that when either plow is raised or lowered its carrying wheel is simultaneously and automatically angled or tilted laterally to a desired and most effective working position. With the left hand plow in the ground its adjacent wheel assumes the laterally inclined position shown in Fig. 4, 5 in which it will be noted that the wheel treads in the corner of the furrow and is in no way liable to tear down the edges of the furrow wall and to become clogged with dirt thereby. Furthermore, the carrying wheel 10 in which it will be noted that the wheel treads in the corner of the furrow and is in no way liable to tear down the edges of the furrow wall and to become clogged with dirt thereby. Furthermore, the carrying wheel 15 when treading in this manner serves to most effectively carry and resist the side strain or thrust of the plow. In this connection it will be noted that the axle bearing because of its inclined position and of the direct 20 manner in which the side strain carried by the wheel, is not subject to the severe uneven wearing strain which the axle of a furrow wheel in upright position would receive. These features all promote lightness of draft 25 since the plow is carried and guided in a most efficient manner and they in no way impede the plowing or present abnormal wearing or working conditions. While I have utilized the segment bracket to effect 30 lateral movement of the carrying wheels, it should be understood that I do not limit myself to this particular method for accomplishing the objects desired since various other means might be employed for the same 35 purpose. Hence various modifications and changes might be made without departing from the spirit and scope of the invention or sacrificing any of its material advantages.

I claim:

- 40 1. In a plow, the combination of a frame, a plow beam mounted thereon and adapted to be raised and lowered, a furrow wheel mounted for rocking movement on a horizontally disposed axis, means including a hand lever coöperating with a notched segment for raising and lowering the plow, the segment being laterally inclined, and connections between the carrying wheel and said lever whereby the same when moved to 45 raise and lower the plow will be swung laterally by means of said inclined segment to tilt the carrying wheel about said axis.
2. In a plow, the combination of a frame, a bail mounted thereon, a plow beam and a carrying wheel mounted on the bail, a hand lever for swinging the bail to raise and lower the plow and carrying wheel, and means coöperating with the lever for causing the hand lever to tilt in a lateral direction to swing the carrying wheel from an upright position to an outwardly inclined position when the plow is lowered.
3. In a plow, the combination of a frame, a bail mounted thereon, a plow beam and a carrying wheel mounted on the bail, and a

lever for swinging the bail to raise and lower the plow and tilttable laterally to move the carrying wheel from a substantially vertical position when the plow is raised to an outwardly canted position when the plow is lowered.

4. In a plow, the combination of a frame, a supporting structure mounted thereon to swing about a horizontal transverse axis, a plow beam and a carrying wheel mounted on the said supporting structure, the carrying wheel being pivotally mounted on said structure so as to be movable from a substantially vertical to an outwardly inclined position, a lever for swinging said supporting structure on its pivot to raise and lower the plow and carrying wheel, and means for tilting the lever laterally to thereby move the carrying wheel from a vertical to said inclined position when the plow is moved to lowered position.

5. In a sulky plow, the combination of a bail, a plow beam and a carrying wheel connected therewith, an operating lever connected with the bail for lowering the plow, and means for tilting the operating lever laterally during its operating movement to cant the carrying wheel laterally.

6. In a sulky plow, the combination of a bail, a plow beam and a carrying wheel connected therewith, an operating lever connected with the bail for lowering the plow, and means for tilting the operating lever laterally during its operating movement to vary the angular relation of the carrying wheel with respect to the frame.

7. In a sulky plow, the combination with a bail, a plow beam and a carrying wheel connected therewith, of means for swinging the bail on its pivot to raise and lower the plow and carrying wheel, a cam way extending longitudinally of the beam and inclined laterally, and means operating between said cam way and carrying wheel to cant the wheel laterally upon movement of the wheel to lowered position.

8. In a plow, the combination of a frame, a bail mounted thereon, a plow beam mounted on the bail, a carrying wheel pivotally mounted on the bail so as to be capable of swinging to different angular positions with respect to the vertical, an operating lever for swinging the bail on its pivot, and a segment fixed to the frame and with which the lever coöperates, said segment having a laterally inclined portion engageable by the operating lever whereby the same will be tilted laterally during its back and forth movements to angle the carrying wheel.

9. In a sulky plow, the combination of a bail, a plow beam mounted thereon, a carrying wheel, said bail having a fore and aft arm upon which the carrying wheel is pivotally mounted, and mechanism for rocking the bail to raise and lower the plow and car-

130

rying wheel and for simultaneously rocking the latter on its said pivotal mounting in such manner that the wheel is moved from a substantially vertical position when 5 the plow is raised to an inclined position when the plow is lowered.

10. In a plow, the combination of a frame, a plow and a furrow wheel vertically movable with respect to the frame, a lever for 10 simultaneously lowering the plow and furrow wheel, and a laterally inclined segment with which the lever coöperates and which causes the lever to be tilted laterally for correspondingly tilting the furrow wheel when 15 the same is lowered.

11. In a plow, the combination of a frame, a vertically movable plow and furrow wheel mounted on the frame, and means for raising and lowering the plow and furrow 20 wheel in unison including a lever movable in a fore-and-aft direction during said raising and lowering operation and tiltable laterally to correspondingly tilt the furrow wheel.

25. 12. In a plow, the combination of a frame, a bail pivotally mounted thereon and equipped with a plow which may be raised and lowered by swinging movement of the bail, a furrow wheel pivotally mounted on 30 the bail on a fore-and-aft axis and adapted to be rocked thereabout from an upright to a laterally inclined position, and means connected with the wheel and bail for moving the latter to lower the plow and furrow 35 wheel and for moving the furrow wheel about its fore-and-aft axis to cant the furrow wheel laterally.

13. In a plow, the combination of a frame, a bail mounted thereon and equipped with

a plow adapted to be raised and lowered by 40 swinging movement of the bail, a furrow wheel pivotally mounted on the bail so as to be movable on its pivotal mounting from an upright to a laterally inclined position, and means for moving the furrow wheel 45 about its pivotal mounting when the bail is moved to raise and lower the plow.

14. In a plow, the combination of a frame, a furrow wheel mounted thereon and capable of vertical adjustment with respect 50 thereto, a lever for moving the wheel vertically, and means whereby the lever may be tilted laterally from the course of its movement in raising and lowering the furrow wheel to cant the same laterally.

55. 15. In a plow, the combination of a frame, a furrow wheel mounted thereon and capable of vertical movement with respect thereto and also capable of being inclined laterally, and means for raising and lowering the furrow wheel including a lever co-operable with a segment extending fore-and-aft and inclined laterally so that during 60 the fore-and-aft movement of the lever the wheel will be raised and lowered and during the lateral movement the wheel will be canted laterally.

65. 16. In a plow, the combination of a frame, a furrow wheel and plow supporting structure movable vertically with respect to the frame and on which structure the furrow wheel is pivotally mounted on a fore-and-aft axis, and means for raising and lowering said structure and for simultaneously moving the wheel about said fore-and-aft 70 axis so as to cant the wheel laterally.

75. LEWIS E. WATERMAN.
